Inventor.
Henry Müller,

Briest & Oppenauer

UNITED STATES PATENT OFFICE.

HENRY MÜLLER, OF WATERBURY, CONNECTICUT, ASSIGNOR TO THE SHOE HARDWARE COMPANY, A CORPORATION OF CONNECTICUT.

BOOT-LAST.

1,296,996.

Specification of Letters Patent. Patented Mar. 11, 1919.

Application filed August 1, 1918. Serial No. 247,705.

To all whom it may concern:

Be it known that I, HENRY MÜLLER, a citizen of the United States, and a resident of Waterbury, county of New Haven, and 5 State of Connecticut, have invented certain new and useful Improvements in Boot-Lasts, of which the following is a full, clear, and exact description.

This invention relates to lasts for manufacturing rubber boots and other articles of 10 footwear. More particularly the invention is directed to lasts wherein the toe or forepart is made separable from the leg or body part to facilitate removal of the last from 15 the completed article.

One means heretofore employed for securing the parts of such lasts together, is a bolt disposed longitudinally of the leg part and formed with a threaded end adapted for 20 screw connection with the forepart. This means is open to the objection that considerable time and labor must be expended to screw the bolt to the forepart and unscrew it therefrom. Another locking means previously employed comprises a curved spring 25 secured to the leg part and adapted to engage a rigid pin on the forepart. This type of construction is open to the objection that a stiff heavy spring must be used to satisfactorily lock the parts together, necessitating the expenditure of considerable physical 30 strength to operate the catch. A further disadvantage of the construction is that due to the employment of but one spring; such 35 spring is required to undergo severe bends in operating the catch with the result that its efficiency is quickly destroyed.

An object of the present invention accordingly is to provide an improved construction free from the various disadvantages noted in connection with the devices hereinbefore described, enabling the forepart of the last to be locked to the leg part with a minimum expenditure of physical 45 effort and time.

Further objects of the invention will hereinafter appear.

Referring to the drawings wherein similar numerals indicate similar parts:

50 Figure 1 is a side elevation partly in section showing the improved construction;

Fig. 2 is a perspective view of the heel portion of the leg part;

Fig. 3 is a perspective view of the forepart, and

55

Fig. 4 is an enlarged detail of the catch. The last illustrated in the drawing comprises a leg part 10 and a forepart 11, divided from the leg part along intersecting vertical and horizontal planes in the usual 60 manner. Both parts are preferably made hollow and may be cast from aluminum alloy or other suitable material.

The vertical face 12 of the heel portion 13 of the leg part is provided with two under 65 cut lugs 14 and 15 adapted to be received between the beveled guide faces 16 formed on the inner end of the forepart 11. The guide faces and lugs fit together in the nature of a dovetail joint, securing the parts against 70 separation in a horizontal direction but enabling the parts to be separated by vertical movement.

For the purpose of yieldingly locking the parts in assembled position a pair of similarly formed coöoperating spring latch members is provided, one of said members being secured by a screw 17 to the lug 15 on the leg part, and the other of said members being secured by screws 18 to the forepart. 75 Each of the latch members embodies a straight flat spring 19 provided with a lug or extension 20 at one end. The lugs 20 are made substantially triangular shape in cross-section to provide front and rear inclined 80 surfaces adapting the lugs to ride over one another in assembling and disassembling the leg and foreparts of the last. In sliding the forepart of the last upon the leg part the front inclined faces of the lugs 20 contact causing 85 the straight springs to yield laterally to permit the lugs to over-ride one another to assume the position shown in Fig. 1, in which position their rear inclined faces are in contact. When in such position the lugs 90 with their associated springs coöperate to hold the fore and leg parts of the last against separation in a vertical direction. In order to unlock the parts the leg part is pulled away from the forepart which operation 100 causes the rear inclined faces of the lugs to force the springs apart permitting one lug to over-ride the other.

In the improved construction both catch members are free to yield to permit the lugs 105 to over-ride one another, which feature pre-

vents the springs from being subjected to undesirable strains and enables the parts of the last to be locked and unlocked with greater ease and more efficient results than 5 has heretofore been possible.

While I have described one of the preferred embodiments of the invention, it is to be understood that various modifications in form, arrangement and materials may be 10 resorted to without sacrificing any of the advantages or departing from the spirit and scope of the invention set forth in the appended claims.

Having thus described my invention what 15 I claim and desire to protect by Letters Patent is:—

1. A boot last comprising a leg part, a detachable forepart, and a catch for securing said parts against relative vertical movement said catch embodying two yielding members one of said members being secured to the forepart and the other of said members being secured to the leg part.

2. A boot last comprising a leg part, a 25 detachable forepart, and a catch for securing said parts against relative vertical movement said catch embodying two yielding members one of said members being secured to the forepart and the other of said members being secured to the leg part, each of 30 said members being provided with an offset face, the offset face on one member being disposed to lockingly engage the offset face on the other member when the parts of the 35 last are in assembled position.

3. A boot last comprising separable leg and foreparts said parts being divided from one another along intersecting vertical and horizontal planes, and a catch embodying 40 two yielding members one of said members being secured to the forepart and the other of said members being secured to the leg part.

4. A boot last comprising separable leg 45 and foreparts said parts being divided from one another along intersecting vertical and horizontal planes and formed with interlocking portions adapted to prevent separation in a horizontal direction, and a catch

embodying two yielding members one of 50 said members being secured to the forepart and the other of said members being secured to the leg part.

5. A boot last comprising separable leg and foreparts said parts being divided from one another along intersecting vertical and horizontal planes, and a catch embodying two yielding members one of said members being secured to the forepart and the other of said members being secured to the leg 60 part, each of said members being provided with an offset face, the offset face on one member being disposed to lockingly engage the offset face on the other member when the parts of the last are in assembled position.

6. A boot last comprising separable leg and foreparts said parts being divided from one another along intersecting vertical and horizontal planes and formed with interlocking portions adapted to prevent separation in a horizontal direction, and a catch embodying two yielding members one of 70 said members being secured to the forepart and the other of said members being secured to the leg part, each of said members being provided with an offset face, the offset face on one member being disposed to lockingly engage the offset face on the other member when the parts of the last are in assembled 75 position.

7. A boot last comprising a leg part, a detachable forepart, and a catch for securing said parts against relative vertical movement, said catch embodying two yielding 80 members, one of said members being secured to the forepart and the other of said members being secured to the leg part, each of said members being provided with two oppositely inclined offset faces, one of the offset faces on one member being disposed to lockingly engage one of the offset faces on the other member when the parts of the last are in assembled position.

Signed at Waterbury, county of New 95 Haven and State of Connecticut, this 24th day of July, 1918.

HENRY MÜLLER.
